COMBINED ELECTRICALLY LIGHTED DICE AND BACKGAMMON BOARD

Charles P. Regensburg, 875 Park Ave.,
New York, N.Y. 10017

Filed Feb. 13, 1974, Ser. No. 442,182

Term of patent 14 years

Int. Cl. D21—01

U.S. Cl. D34—5 SS

FIG. 2

FIG. 3

FIG. 4

FIG. 1 is a top perspective view of a combined electrically lighted dice and backgammon board showing my new design;

FIG. 2 is a top plan view;

FIG. 3 is a side elevational view; and

FIG. 4 is an end elevational view.

The broken line of the power cord indicates indeterminate length.

I claim:

The ornamental design for a combined electrically lighted dice and backgammon board, as shown and described.
